AIR CONDITIONING SYSTEM

Clyde M. Hamblin, Washington, D. C.

Original application January 21, 1943, Serial No. 473,052. Divided and this application February 6, 1947, Serial No. 726,944

12 Claims. (Cl. 98—38)

(Granted under the act of March 3, 1883, as amended April 30, 1928; 370 O. G. 757)

1

This is a division of my copending application Serial No. 473,052, filed January 21, 1943.

This invention relates to fan-operated heating and cooling systems. In conventional fan-operated heating and cooling systems the temperature of the air delivered is often controlled, or partially controlled, by providing means for bypassing part of the air used around the heating or cooling coils. In such systems part of the air is usually fresh air drawn from the outside, and part is drawn from the spaces served, and recirculated through the heating or cooling system.

In the known conventional types of heating and cooling systems described above, all of the air, both fresh and recirculated, which passes through the heating or cooling coils and through the by-pass also passes through the fan. As the air which is by-passed around the heating or cooling coils, or that which is recirculated or is drawn from the outside air, is usually a considerable portion of the total capacity of the system, these conventional types or arrangements involve the use of fans of unnecessarily large size or capacity.

It is an object of my invention to provide means whereby air can be by-passed around the heating or cooling coils, or may be drawn from the outside, or from the spaces served, without such air passing through the fans, thus permitting a considerable reduction in the size or capacity and weight of the fan used. This is particularly important on shipboard and similar places where the utmost saving in space and weight is necessary.

It is a further object of my invention to provide means for limiting and regulating the difference between the temperature of the air leaving the heating or cooling coils and the temperature of the space or room served.

In the accompanying drawings forming part of the present specification:

Fig. 1 shows a diagrammatic view in elevation of a fan-operated heating or cooling system with the heating or cooling coils located on the intake side of the fan.

Fig. 2 shows a diagrammatic view in elevation of a fan-operated heating or cooling system with the heating or cooling coils located on the discharge side of the fan.

Fig. 3 is a diagrammatic view in elevation of a modified form of the present invention somewhat similar to Fig. 2, but which is distinguishable therefrom.

Fig. 4 is a diagrammatic view in elevation of a modified form of the present invention somewhat similar to Fig. 1.

Referring more in detail to the drawings and more particularly to Fig. 1; there is shown at 10 a ventilating fan driven by a motor 11 or other

source of power and heating or cooling coils 12 mounted in a duct system of air conditioning 13 connected to the intake side of the fan 10. A duct 14 is connected to the discharge side of the fan 10 and delivers the heated or cooled air to outlets 15 in the space or room to be heated or cooled. The outlets are served by one or more distribution ducts 16, 16. The intake end of the fan intake duct system 13 may draw air from the outside atmosphere, from the spaces served such as rooms or the like, or from both. A by-pass 17 is provided which passes around coils 12 from the intake duct 13 to an opening 18 in the discharge duct 14. A hinged damper or baffle plate 19 is provided at the opening 18 and is so designed and arranged that as the damper is moved to admit air from by-pass 17 through the opening 18, duct 14 is simultaneously or independently restricted by the damper, thereby causing an increase in air velocity in the duct 14 and a consequent change in static pressure, and velocity pressure relations, in duct 14 which will induce a flow of air from the by-pass 17 through the opening 18.

An operating handle 20 is provided on the damper hinge shaft 21 for adjusting the damper opening 18 as necessary to obtain the proper relation or proportion of air flow through the heating or cooling coils 12 and the by-pass 17 for any required air temperature desired.

An additional or alternate arrangement to by-pass 17 and damper 19 may be provided, as shown in Fig. 1 of the drawings, consisting of a damper 23 which controls a supply of induced air 35 through the opening 24 from any desired source.

Similar adjustable throttling dampers 25 are arranged to induce air flow through openings 26 in ducts 16, 16 preferably within the spaces or rooms served, to which air is delivered, to limit 40 or control the difference between the temperature of the air delivered from the outlets 15, 15 and the temperature of the space or room to which the air is finally delivered. This is particularly important in cooling and air conditioning systems in order to avoid the sensation of cold drafts.

Any one opening with damper or any combination of openings with dampers described may be used in a system as best suits the conditions to be met.

Referring now in detail to the arrangement of parts shown in Fig. 2;

The arrangement of the various parts shown in the arrangement of Fig. 2 is similar to that shown in Fig. 1, except that the heating or cooling coils shown in Fig. 2, are on the discharge side instead of on the intake side of the fan 30. In said Fig. 2 the numeral 31 indicates the motor or other source of power used to drive the fan 30. The numeral 32 indicates the by-pass from duct 33 to

duct 34. Said duct 32 is similar to duct 17 of Fig. 1 and is provided with a damper hingedly mounted at 36 preferably in the duct 34, and provided with an operating handle 37, as shown. It is readily seen as in the case of Fig. 1, opening 38 and duct 34 are readily adjusted to permit or induce the air in by-pass 32 into the duct 34 as desired. Numeral 39 indicates the cooling or heating coils used on the discharge side of the fan 30 and which is connected by duct 40 with said fan, as shown. In the duct 40 are mounted two dampers 41, 42 hingedly mounted at 43, 44 in the duct 40. It is seen that inlets 45, 46 admit air to the cooling or heating coils 39 in desired quantities from any desired source. The duct 34 may be provided with any plurality of ducts 47, 47 for the purpose of distributing the air from duct 34 into any served space by means of outlets 48, 48 etc. At 49 is shown a duct having a damper 50 hinged at 51 having a handle 52 which is alternative or added structure to be used with or without the by-pass 32. The air admitted through damper 50 may be from any desired source. Other dampers 53, 53 may be used to control the flow of air to the outlets 48, 48.

It will be noted that the by-pass ducts 17 and 32 in Figs. 1 and 2 respectively, lead air from inlet ducts 27 and 33 respectively to ducts 14 and 34 respectively, and the air so obtained is taken from the intake ducts prior to passing air through the heating or cooling coils 12 or 39 respectively. It will also be noted in Fig. 1 that a by-pass 54 leads from the portion 55 of the intake duct 27 and conveys air to the duct 14 through the opening 56, which is controlled by damper 57, which is hingedly mounted at 58 in the duct 14. The air in duct 54 is taken from the intake duct 27 after said air is passed through the heating or cooling coils 12.

In Fig. 1 it is evident that air may be supplied to the duct 14 from the duct 27 either before or after the air therein passes through the heating or cooling coils 12, which provides a means of control for the amount and temperature of the induced air required in duct 14, as is found to be most useful in the delivery of air through the outlets 15, 15 etc.

Referring now to Figs. 3 and 4 of the drawings:

The purpose of the arrangements shown in Figs. 3 and 4 is to permit larger quantities of air to pass through the heaters than through the fans. Such arrangements may be of advantage where less fresh air is required for ventilation than the total air circulation necessary for heating, as shown in Fig. 3. Also in the case of Fig. 4, a system is shown for handling a larger volume of heated air at low pressure.

In both of the arrangements shown in Figs. 3 and 4, fans may be used to handle less air than is passed through the heaters, but at relatively higher pressure. It will be noted that all air from the intake duct passes through the heating or cooling coils prior to its final delivery at 97 in the delivery duct 59 of Fig. 3 and 73 of Fig. 4. It will be noted in Fig. 3 that 60 indicates the intake duct which leads to the fan 61 and thence to the duct 59 from whence the air passes through the heating or cooling coils 62 prior to delivery to the pipes (not shown) which correspond to the ducts 16, 16 of Fig. 1 or 47 of Fig. 2. The numeral 63 represents the usual motor for driving the fan 61, in Fig. 3, as is readily understood.

It is noted that dampers 64, 65, Fig. 3, hinged at 67, 68 respectively, admit air from any desired

external source into the duct 59 for control of the air which passes through coils 62.

With reference to Fig. 4 of the drawings, 69 indicates the heating or cooling coils, duct 70, the duct leading therefrom, conveys air to the fan 71 which is operated by the motor 72 and the propelled air eventually reaches duct 73. A by-pass 74 leads from duct 70 to delivery duct 73, as shown, and a damper 75 hinged at 76 with a handle 77 permits the flow of air from intake duct 70 into duct 73.

In the arrangements shown in Figs. 3 and 4 of the drawings, it will be noted that all the air delivered from the supply system through outlets 15 corresponding to 16 and 48 of Figs. 1 and 2 respectively, passes through the heating or cooling coils of the system since the last-named two systems of Figs. 3 and 4 permit larger quantities of air to pass through the heater and cooling coils than are passed through the fans.

In Fig. 3, the heating or cooling coils are located on the discharge side of the fan 61 and it will be noted the adjustable dampers 64, 65 are so arranged that when opened they increase the velocity of air in the duct 59 and induce an inflow of air through the openings controlled by said dampers. The said openings and dampers just named, function in similar manner to other similar induced air openings and dampers in the present air systems.

In Fig. 4, the heating or cooling coil 69 is located on the intake side of the fan 71 and it is necessary to by-pass the fan using the duct 74 in order that more air may pass through the coil 69 than is passed through the fan 71. In this case the induced air control opening is shown at 78 adjacent to baffle-plate or damper 75.

Attention is called to the fact that while the description and claims herein describe the means for tempering the air, i. e., a heating means, and the "external air" largely assumed as being of a lower temperature than the normal air stream within the air conditioning system, it will be at once apparent that the so called heating means 40 (such as 12 Fig. 1, 39 Fig. 2, 62 Fig. 3, 69 Fig. 4) may be representative of cooling coils or means and the external induced air may be considered of an equal or higher temperature than the normal air stream within the air conditioning ducts 50 of the system. In such cases as those just explained it will be evident the effect of the introduction of "external" air on the normal air stream within the system will have a reverse effect than when the coils 12, Fig. 1, etc., are heating coils, 55 and the "external" air used is of lower temperature than the normal air stream within the air ducts of the conditioning system. The claims are to be interpreted with the above explanation in view, when it is desired the present system is to be used as an air cooling system instead of an air heating system.

The term "air conditioning" as used herein is intended to be used in its broad sense, to include heating, cooling, humidifying or de-humidifying 65 air or fluids, or any combination of these operations. For instance the parts indicated by numerals 12, 39, 62 and 69 of the Figures 1 to 4 respectively, may be made as heating or cooling coils, air washers, humidifiers, or de-humidifiers, or any combination of these devices.

Attention is also directed to the purpose of the use of the multiple air inlets and dampers, instead of merely single ones, as shown by parts 45, 46, 41, 42 in Fig. 2, and in similar instances in the drawings, which is to distribute as uniformly as pos-

sible the "external" air introduced by these inlets into the normal airflow within the air conditioning system.

The invention described herein may be manufactured and used by or for the Government of the United States of America for governmental purposes without the payment of any royalties thereon or therefor.

I claim:

1. In an air heating and cooling system, a circulating fan and means for operating same, an air duct connected with the fan on the intake side thereof, means in the intake duct for heating the air passing to the fan, a discharge duct connected with the fan, a by-pass duct connected with the air intake duct, whereby the said by-pass duct may remove air from the latter duct prior to admission of air to the heating means and the circulating fan, and deliver the removed air to the discharge duct without being heated, or propelled by the fan, means in the discharge duct adjacent to the by-pass inlet thereto, adapted to adjustably control the flow of induced air from the by-pass duct, whereby the proportion between the propelled and induced air in the discharge duct may be varied, for the triple purpose of controlling the temperature of the air delivered by the system, varying the total heat output of said system, and controlling the velocity of flow of the finally delivered air stream.

2. In a system as described in claim 1, in combination with a by-pass duct connected with the air intake duct, adapted to withdraw air from the said duct after it has passed through the heating means and has been raised in temperature to any desired degree, and prior to admission of air to the circulating fan, and deliver the by-passed air to the discharge duct without being propelled by the fan, means in the discharge duct adjacent to the inlet of the second-described by-pass duct thereto, adapted to adjustably control the flow of air from said last-named by-pass duct, for the purpose of adjustably supplying heated air from the intake duct directly to the discharge duct, and to vary the proportion between the fan-propelled air, induced air from the first-named by-pass duct, and the heated induced air from the second-named by-pass duct, for the purpose of further temperature, velocity of flow, and heat output control of the air delivered by the system, and for reducing the proportionate amount of air required to be propelled by the circulating fan.

3. In an air heating and cooling system, a circulating fan and means for operating same, an air intake duct connected with the fan, a discharge air duct connected with the fan, means connected with the discharge duct for heating the air in the latter, a by-pass duct connected with the intake duct for removing air from the latter prior to admission of the intake air to the fan, adapted to deliver said by-passed air to the discharge duct after the fan-propelled air has passed through the heating means, and adjustable means mounted in the discharge duct adjacent to the bypass inlet thereto, adapted to control the flow of induced by-passed air into the discharge duct, whereby the proportion between the propelled and heated air, and induced by-passed air may be varied for the purpose of controlling the temperature of the air delivered by the system, varying the velocity of flow in the discharge duct, and varying the total heating output of said system.

4. In a system as described in claim 3, in combination with adjustable induced air control

means mounted in the discharge duct between the circulating fan and the heating means, for mixing external air with the fan-propelled air in the said discharge duct prior to its passing through the heating means.

5. In an air heating and cooling system as described in claim 1, an adjustable means for admitting induced external air into the discharge duct after the flow of mixed air has passed the inlet of the by-passed induced air, and a plurality of delivery ducts each connected with the discharge duct of the system.

6. In an air heating and cooling system as described in claim 3, an adjustable means for admitting induced external air into the discharge duct after the flow of mixed air has passed the inlet of the by-passed induced air, and a plurality of delivery ducts each connected with the discharge duct of the system.

7. In an air conditioning system having an inlet duct, means for circulating air, means for conditioning air, distribution ducts for conveying the conditioned air and outlets for distributing the air, at least one of said distribution ducts having at least one lateral opening therein for admitting unconditioned air, and air inducing means comprising an adjustable damper pivotally mounted adjacent the upstream edge of said lateral opening in said distribution duct and adapted to swing inwardly of said duct into open position with respect to said opening to induce a flow of air inwardly through said opening by the action on said damper of the flow of conditioned air in said duct, whereby the temperature of the conditioned air and the heat output of the system are adjustably controlled.

8. In an air conditioning system as described in claim 7, a duct connected to an induced air inlet opening with damper, for adjustably admitting air from a location remote from that in which the induced air inlet opening and damper are located.

9. In an air conditioning system as described in claim 7, having the air conditioning means in said inlet duct on the inlet side of the air circulating means, a by-pass duct one end of which is connected to a lateral induced air inlet opening with damper in said distribution duct and the other end to the said inlet duct on the inlet side of the air conditioning means.

10. In an air conditioning system as described in claim 7, having the air conditioning means in said inlet duct on the inlet side of the air circulating means, a by-pass duct one end of which is connected to a lateral induced air inlet opening with damper in said distribution duct on the discharge side of the air circulating means and the other end to the said inlet duct between the air circulating means and the air conditioning means.

11. In an air conditioning system as described in claim 7, having the air conditioning means in the said distribution duct on the discharge side of the air circulating means, a lateral induced air inlet opening with damper in the duct between the air conditioning means and the air circulat-

ing means.

12. In an air conditioning system as described in claim 7, having the air conditioning means in the said distribution duct on the discharge side of the air circulating means, a by-pass duct one end of which is connected to a lateral induced air inlet opening with damper in said distribution duct on the discharge side of the air conditioning means and the other end to the said inlet duct on the inlet side of the air circulating means.
